UNITED STATES PATENT OFFICE.

IRA E. SMITH, OF STOCKTON, CALIFORNIA.

WATER-FEED-CONTROL SYSTEM FOR BOILERS.

Application filed June 20, 1927. Serial No. 199,990.

This invention relates to systems for feeding water into steam boilers as the supply of water in the boiler becomes depleted by the generation and consumption of steam; 5 my principal object being to provide an apparatus for the purpose which comprises an electric switch, a pressure actuated unit associated therewith, and a water feed control valve or other device operated by the switch, so arranged and connected to the boiler that as the steam is generated and consumed and the water level lowered the switch will be automatically closed and the water caused to enter the boiler; and when 10 the normal height of water is reached in the boiler the switch will be automatically opened, causing the inflow of water to the boiler to cease.

The apparatus requires no attention and 20 will work constantly and within a very close range so that there is no danger of the water in the boiler ever dropping to such a level as to become dangerous.

A further object of the invention is to 25 produce a simple and inexpensive device and yet one which will be exceedingly effective for the purpose for which it is designed.

These objects I accomplish by means of such structure and relative arrangement of 30 parts as will fully appear by a perusal of the following specification and claims.

In the drawings similar characters of reference indicate corresponding parts in the several views.

35 Fig. 1 is a side elevation of the apparatus shown in connection with an ordinary form of stationary steam boiler.

Fig. 2 is an enlarged side elevation partly in section of the control mechanism showing 40 the parts in their normal positions and with the switch opened.

Fig. 3 is a side elevation of the control mechanism showing the switch closed.

45 Fig. 4 is a side elevation of the water feed pipe valve control mechanism.

Referring now more particularly to the characters of reference on the drawings, the numeral 1 denotes a steam boiler of ordinary character associated with which is the 50 usual water column 2 which is connected to the steam space of the boiler by a top pipe 3 and with the water space of the boiler by a bottom pipe 4. The normal water level line in the boiler is indicated at W, the water

of course being the same level in the column 2. 5 denotes a water feed pipe leading to the boiler from any suitable source of supply and under sufficient pressure for the purpose.

My improved water feed control structure comprises an electric switch preferably of the mercury contact type which consists of a mercury tube 6 into one end of which a pair of separated contacts 7 project. This tube is supported intermediate its ends for 60 longitudinal rocking movement by a bracket 8 pivoted in a casing 9. An arm 10 projecting horizontally from the bracket is connected by a link 11 to a horizontal lever 12 which is pivoted intermediate its ends in 65 the casing and projects outwardly from one side thereof. Inside the casing a spring 13 bears down on the lever, these parts being arranged so that when the spring is free to act the tube will be tilted so that the mercury will flow toward the contacts and will 70 engage the same.

Secured to the outer end of the lever is a hollow vessel 14 whose weight when empty is not sufficient to overcome the pressure of the spring 13 but which will overcome such pressure when full of water. Mounted on top of the vessel is a relief valve 15 of standard form which is closed either by heat acting on a diaphragm 16 and causing a float 17 to rise (said float having a valve member 18) or by water acting directly on the float 75 independently of the diaphragm action.

Between the relief valve and the vessel 14 a pipe line 19 is connected which extends downwardly to a connection with the column 2 just below the water level line W. From the bottom of the container 14 a pipe line 20 extends to a connection with the column 2 at any point below the connection of the pipe 19 therewith. Portions of both pipe lines adjacent the vessel 14 are made of flexible tubing as shown at 21 so as not to interfere with the necessary limited vertical tilting of the vessel. This apparatus is set some distance above the boiler so that the water in the vessel will tend to flow from the same by gravity.

Mounted in the casing 9 under the lever 12 is another lever 22 which is pivoted intermediate its ends in the casing. At one end a spring 23 acts on the lever 22 to raise said end, the other end being engaged by a head

24 provided in connection with a diaphragm 25 which is arranged to be expanded by steam, so that the head 24 will be raised.

A rigid steam pipe 26 (also serving to support the casing) is connected to said diaphragm and extends thence to a connection with the steam pipe 3. An upstanding stop lug 27 on the lever 22 between the pivot thereof and the spring 23 normally bears 10 against the under face of the lever 12. The strength of the spring 23 is sufficient to overcome the action of the spring 13 when the vessel 14 is empty so as to maintain the adjacent end of the lever 12 raised and hold 16 the switch in its open position. When the diaphragm is expanding by steam however the adjacent end of the lever 22 is raised, lowering the opposite end thereof and the stop 27 against the resistance of the spring 20 23 and permitting the lever 12 to drop if the conditions are such that this action will take place.

The closing of the switch controls the 25 operation of a water feed control device, and while various mechanisms may be used for this purpose, in the present instance I have shown this device as being a valve 29 in the water line 5. The stem 30 of this valve is normally held in closed position by a 30 spring 31, said stem being connected to an arm 32 which is mounted in connection with the pivoted armature 33 of a magnet 34 which is supported in fixed relation to the pipe and valve by a bracket 35 or the like.

35 These parts are disposed so that when the valve is closed the armature is spaced from the core of the magnet, the energizing of the latter drawing said armature theretoward and causing the valve to be opened, thereby 40 allowing the water under pressure in said pipe to pass by the valve and enter the boiler. Wires 36 from the main power lines 37 to the magnet have the switch contacts 7 interposed therein, as illustrated diagrammatically in Fig. 1.

In operation assuming the water in the boiler to be at the proper level and cold, there will be no water in the vessel 14, since 50 when there is no steam pressure in the boiler the water will drain from the vessel by gravity. The contacts 7 are therefore open and all the parts of the apparatus are in the positions shown in Fig. 2.

55 As soon as steam is raised in the boiler, while the water therein is still above the level of the connection of the pipe 19 with the column 2 (which is the equivalent of the boiler), water will be forced into the vessel 14 and held therein by such steam pressure and its weight will be added to that of the vessel itself overcoming the spring 13. At the same time the steam expands the diaphragm 25 causing the stop 27 to drop away from the lever 12 and said stop will remain in this position as long as there is any steam

pressure in the boiler. The lever 12 however will remain at this time in a switch opening position owing to the weight of the water in the vessel. As soon as the pipe 19 at the boiler becomes uncovered by the lowering of the water in said boiler, the steam will enter said pipe, passing into the top of the vessel, and will drive the water out of said vessel through the bottom pipe 20 and back into the boiler. The vessel 14 being thus relieved of its weight of water, the spring 13 is free to function and will therefore lower the adjacent portion of the lever 12 so as to tilt the mercury tube to a contact closing position, as shown in Fig. 3. This energizes the magnet 34, causing the water feed valve to be opened, as previously explained.

The water in the boiler therefore rises until the pipe 19 becomes closed by said water, when the flow of steam to the vessel 14 will be cut off, causing whatever steam is still in the vessel to condense. This permits the vessel to again refill with water due to the pressure of the live steam thereon at the boiler end of the pipe 19. As soon as the vessel is full of water its weight causes the lever 12 to be tilted in the opposite direction, opening the switch and causing the feed of water to be discontinued.

These movements take place intermittently 95 as long as water is being used from the boiler and steam is being generated. As soon as the steam generation ceases the diaphragm 25 returns to its normal position, causing the spring 23 to act and raise the stop 27 against the lever 12, preventing the latter from being depressed to a switch closing position until steam is again generated, and regardless of the empty or full condition of the vessel 14.

The relief valve 15 serves an important 100 purpose, and is essential in making the device fully automatic in action. When the boiler and system are relatively cold, and there is no steam pressure on the water, the originally hot water in the vessel, upon cooling off, will contract and drop away from the float 17, opening the air vent and allowing the water to flow back to the boiler by gravity. When steam is again generated in the boiler and the water is forced up into the vessel, the open valve will allow the air to escape and the water to take its place. When the level of the water in the boiler 110 drops, permitting steam to enter the vessel and expel the water, the heat of the steam acts to expand the diaphragm 16 and hold the float in a valve-closing position, even if said diaphragm is not already expanded by the heat of the water.

From the foregoing description it will be 125 readily seen that I have produced such a device as substantially fulfills the objects of the invention as set forth herein.

While this specification sets forth in detail the present and preferred construction

of the device, still in practice such deviations from such detail may be resorted to as do not form a departure from the spirit of the invention, as defined by the appended 5 claims.

Having thus described my invention what I claim as new and useful and desire to secure by Letters Patent is:

1. A water-feed control system for a steam boiler including a normally open electric switch, a water feed device controlled by the closing of said switch, a rockable lever, means between the lever and switch for causing the latter to be opened when the lever is tilted in one direction and vice versa, means acting on said lever tending to tilt it in a switch closing direction, steam released stop means normally preventing the lever from thus being tilted, a vessel supported by the outer end of the lever and tending to tilt the lever in a switch opening direction; the weight of said vessel when empty being insufficient to overcome said first named tilting means but causing said 25 first named means to be overcome when the vessel is full of water, means causing said vessel to be filled with water when the water in the boiler is at a predetermined level, and means causing the vessel to be emptied of such water when the water in the boiler drops below such level.

2. A water-feed control system for a steam boiler including a normally open electric switch, a water feed device controlled by the closing of said switch, a rockable lever, means between the lever and switch for causing the latter to be opened when the lever is tilted in one direction and vice versa, means acting on said lever tending to tilt it in a switch closing direction, steam released stop means normally preventing the lever from thus being tilted, a vessel supported by the outer end of the lever and tending to tilt the lever in a switch opening direction; the weight of said vessel when empty being insufficient to overcome said 45 first named tilting means but causing said first named means to be overcome when the

vessel is full of water, a pipe from the top of said vessel to the boiler just below the 50 full-water level therein, and a pipe from the bottom of the vessel to the boiler at a point below the connection of the first named pipe therewith.

3. A water-feed control system for a steam boiler including a normally open electric switch, a water feed device controlled by the closing of said switch, a rockable lever, means between the lever and switch for causing the latter to be opened when the lever is tilted in one direction and vice versa, means acting on said lever tending to tilt it in a switch closing direction, another rockable lever under the first named lever, a stop lug on the under lever bearing against 65 the upper lever and preventing movement of the same in a switch closing direction, a spring acting on the under lever to hold the lug in engagement with the upper lever and overcoming the action of said upper lever 70 tilting means, an expansible diaphragm engaging the under lever to move the same against the pressure of the spring when the diaphragm is expanded, a steam pipe connected to the diaphragm and communicating 75 with the steam chamber of the boiler, means functioning independently of the steam-released lug for preventing the upper lever from tilting in a switch closing direction as long as the water in the boiler is at 80 a predetermined level, and means allowing said lever tilting means to function when the water in the boiler drops below said level.

4. A structure as in claim 1 in which the 85 vessel is provided with a normally open air-intake valve, arranged to automatically close when the vessel fills with water.

5. A structure as in claim 1, in which the vessel is provided with a normally open 90 air-intake vent, and means to close the vent both when the vessel fills with water and independently with the presence of a certain high temperature in the vessel.

In testimony whereof I affix my signature.

IRA E. SMITH.
